COUPLING FOR COAXIAL CABLES

Augustus S. True, Larchmont, N.Y., assignor to Sealectro Corporation, Mamaroneck, N.Y., a corporation of New York

Application February 12, 1958, Serial No. 714,723

2 Claims. (Cl. 339—177)

This invention relates to connectors for coaxial cables and relates more particularly to improved means for securing a firm electrical contact with the braided metal sheath forming the outer conductor without exerting pressure on or otherwise deforming the inner insulation jacket on the axial conductor which would tend to vary the electrical characteristics of this cable.

The invention is illustrated as being embodied in the male section of a male and female detachable connector for coaxial cables but the invention is by no means confined to this particular use.

Certain techniques have been employed for making an effective connection with the outer conductor in the larger cables but these methods have not been satisfactory in miniature and sub-miniature coaxial cables and the exertion of pressure on the braid and hence on the inner insulation and conductor by the use of a constricting clamping arrangement produces changes in the electrical characteristics of the cable. Also the methods heretofore used have not afforded sufficient resistance to a pullout force sometimes exerted on the cable.

An important object of the present invention is to provide means for obtaining a firm clamping contact with the braided metal of the coaxial conductor without transmitting this force radially inwardly of the cable.

Another object of the invention is to provide a simultaneous clamping action on both the braided sheath and the cable jacket to enable the assembly to withstand a pullout force on the cable substantially equal to the breaking strength of the cable.

A further object of the invention is to provide a coaxial connector which can be installed on the end of the cable in a very minimum amount of time and without the use of special tools.

Yet another object of the invention is to provide an assembly which can be disassembled and repaired in the field.

In the drawing:

Fig. 1 shows a longitudinal section through one section of a connector embodying the present invention.

Fig. 2 is a similar section showing a slightly modified arrangement.

A flexible coaxial cable is shown at 10. This cable includes a central or axial conductor 11, an inner insulation jacket 12, an outer coaxial conductor or electrical sheath 13 which may be of woven or braided copper wire construction, and an external layer of plastically deformable insulation 14.

The male connector comprises a two-part tubular housing including male and female tubular metal members or sleeves 15 and 16, the former having a longitudinal bore 17 of such diameter as to receive the coaxial cable 10 with a free fit. The sleeve is externally threaded at 20 and has a non-circular wrench-receiving surface 21.

The female sleeve 16 has a bore 22 extending from its inner end and which is internally threaded at 23 to receive threads 20. About midway on the sleeve the bore has an annular shoulder 24 and a bore section 25 of re-

duced diameter extending to its outer end. The sleeve has a reduced outer diameter shown at 26 which is externally threaded at 27 and has an outer-terminal section 30 of about the same diameter as section 26.

5 The contact for the axial cable 11 which forms no part of the present invention is illustrated as comprising a male contact member which may be formed in a single piece and includes, starting at its outer end, a contact portion 31, a section 32 of enlarged diameter, a shouldered portion 33, and a wire-receiving sleeve 34 at its inner end. For the sake of clarity the wire-receiving sleeve portion 34 is shown in section and the remaining portions in elevations. The shouldered portion has a transverse opening 35 through which the forward end

15 of the axial conductor 11 passes and is soldered therein. The inner insulation jacket 12 is removed as far as line 36 where the axial conductor enters sleeve portion 34.

An insulating sleeve 41 having an enlarged counter-bore section 42 encloses sleeve 34 and the end of inner insulation jacket 12. When this jacket is removed from the cable back as far as line 36, the braided conductor is also removed back this far and the braid of the terminal section 43 is straightened and flared outwardly at right angles.

20 25 A sleeve 44 forming one of the principal structural elements of the present invention is now slid over the insulation jacket and back between the braid and said jacket. This sleeve has an inner diameter as to fit snugly over the insulation and has an annular flange 45 at its outer end which fits within bore 22 of male coupling sleeve 15.

25 30 Another important structural element of the present invention is a sleeve 50 formed of resilient but non-compressible material and at each end of this sleeve

35 metal washers 51 and 52 are positioned in order to prevent rotation imparted to either of the relatively rotatable members 15—16, in tightening the assembly, to be imparted to the sleeve 50 and thus distort it by torsional forces. The outside diameter of the sleeve is substantially the same as that of bore 22. Various materials can be used for forming sleeve 50 and the essential characteristic of such material is that it be capable of yielding under pressure without bringing about a reduction of its total volume. Such materials include silicone rubber, neoprene and Buna-S.

40 45 At the outer end of the male connector assembly an insulator 53 is received in snug fit relation in the outer end of bore 25 in tubular member 16 which has a bore 54 to receive second section 32 of the male connector 31 and a counter-bore 55 at its outer end.

50 55 In assembling the parts, the cable is moved into male coupling sleeve 15 a distance one or two inches to the right of the position shown in Fig. 1. Washers 51—52 with the resilient sleeve 50 therebetween are now placed on the outer insulation 14.

55 60 The metal sleeve 44 is now slipped into the annular area between the braid which has now been straightened, and the inner insulation jacket. The cable is now drawn to the left to the position of Fig. 1 and the terminal section 43 of the braid is between washer 52 and flange 45.

65 70 Insulation 41 is now fitted in place and the inner conductor is moved into opening 34 and soldered. Insulator 53 is next assembled on section 32 of the male contact 31 and the entire assembly of parts is now inserted in the coupling sleeve 16 and the threaded inner sleeve or clamping nut 15 is turned into the threaded section 23 of the outer coupling. Continued relative rotation of coupling sleeves 15—16 causes the washers 51—52 to press against opposite ends of resilient sleeve 50 and since the material forming the sleeve cannot be displaced outwardly because of the close fit between bore 22 and the outer periphery of the sleeve, it must travel inwardly

against the outer insulation jacket 14, compressing it and the braid against metal sleeve 44. This action also compresses braid terminal 43 between washer 52 and flange 45. This compressive action of the braid against sleeve 44 is not transmitted to the central conductor or its insulation because the sleeve has sufficient compressive strength to resist deformation when the stresses are applied equally around its entire periphery. It will be appreciated that the principal purpose of the washers 51-52 is to facilitate relative rotation between the two parts of the tubular housing and that if these washers are omitted the internal shoulders will move against the ends of the plastic sleeve and compress the ends toward each other.

The female section of the connector may be the same as the male connector insofar as the contact means for the braid or outer conductor is concerned. Accordingly only a fragmentary showing of the female connector is made and this includes a female connector member having an outer section 60 to receive male portion 31, a shouldered section 62 similar to section 33 and having a solder opening 63 and an inner sleeve section 64 to receive central conductor 65.

The female connector is received in an insulator 66 and the whole is enclosed in an outer sleeve 70 having a forward section 71. A coupling sleeve 72 having internal threads 73 received on threads 27 of coupling sleeve 16 is flared inwardly at 74 to complete the assembly. If desired, female sleeve 60 may have longitudinal slots (not shown) to cause it to exert a constrictive action on the male contact 31.

Fig. 2 shows only a slight modification in the construction of the connector. Coupling sleeve 78 with its wrench receiving surface 79 is similar to coupling sleeve 15. The coaxial cable including central conductor 80, inner insulation 81, braid 82 and outer insulation 83 is the same as that shown in Fig. 1 and the bore 84 in coupling sleeve is shown as having a larger diameter than the cable. The other coupling sleeve 85 has the same threaded engagement 86 with coupling 78 and has a bore 87 shown as having a larger diameter than resilient sleeve 90 and washers 91-92. The metal sleeve 93 which fits over inner cable insulation 81 has flange 94 and the section 95 of the braid overlying sleeve 93 is shown as being outwardly displaced from the remainder of the braid. The braid terminal 96 is positioned between washer 92 and flange 94. It will be appreciated that as the coupling sleeves 78-85 are rotated relative to each other the material of the resilient ring moves outwardly until it fills the void, after which it moves inwardly, firmly compressing the braid against sleeve 93 and flange 94.

While there have been described herein what are at present considered preferred embodiments of the invention, it will be obvious to those skilled in the art that many modifications and changes may be made therein without departing from the essence of the invention. It is therefore to be understood that the exemplary embodiments are illustrative and not restrictive of the invention, the scope of which is defined in the appended claims, and that all modifications that come within the meaning and range of equivalency of the claims are intended to be included therein.

What I claim is:

1. A connector for the outer conductor of a coaxial cable provided with an inner insulation between inner and outer conductors and an insulating jacket over the latter, said connector comprising a metal tube of substantially uniform diameter throughout its length, positioned between the outer conductor and the inner insulation, a plastically deformable sleeve enclosing the outer

insulation in the area of the metal tube and extending at each end thereof to a point which is not beyond the adjoining end of the tube, a two-part tubular enclosure for the deformable sleeve and having a screw threaded engagement therebetween and provided with internal shoulders, and a washer of the same internal and external diameter as the deformable sleeve positioned at each end of said sleeve, whereby relative rotation between the two parts of the tubular enclosure forces the washers against the ends of the plastic sleeve and moves the ends thereof toward each other without any appreciable longitudinal movement of the sleeve relative to the outer insulation, the bore in the enclosure initially being of such size as to receive the sleeve in snug-fit relation and characterized by an absence of voids inside and outside the sleeve so that all of said compressive action moves the plastic mass radially inwardly, firmly compressing the outer insulation against the outer conductor and the latter against the metal tube and effecting firm electrical contact therebetween and exerting sufficient compression of the outer conductor between the outer insulation and the metal tube as to prevent a pull-out of the cable when a force substantially equal to its tensile strength is applied thereto, the metal tube being sufficiently strong to resist deformation when the compressive force is applied to the plastic sleeve and thus avoid transmitting said compressive force to the central conductor and its insulation.

2. A connector for an outer braided conductor of a coaxial cable provided with an inner insulation between inner and outer conductors and an outer insulation over the latter, said connector comprising a metal tube of substantially uniform diameter throughout its length positioned between the outer conductor and the inner insulation and having a flat annular flange at its forward end contacted by the ends of the braided conductor in the area of the metal tube, a plastically deformable sleeve enclosing the outer insulation in the area of the metal tube and extending at each end thereof to a point which is not beyond the adjoining end of the tube, a two-part tubular enclosure for the plastic sleeve and having a screw threaded engagement therebetween and provided with opposed, internal shoulders, and a washer of the same internal and external diameter as the deformable sleeve positioned at each end of the sleeve, whereby said relative rotation between the two parts of the tubular enclosure forces the washers against the ends of the plastic sleeve and moves the ends thereof toward each other without any appreciable longitudinal movement of the sleeve relative to the outer insulation, the bore in the enclosure initially having a snug-fit relation with the deformable sleeve and characterized by an absence of voids inside and outside the same, so that all of said compressive action moves the plastic mass radially inwardly, firmly compressing the outer insulation against the outer conductor and the latter against the metal tube and effecting firm electrical contact therebetween and between the ends of the braided conductor and said flat annular flange, and exerting a sufficient compression of said braided conductor against the tube and its flange as to prevent a pull-out of the cable when a force substantially equal to its tensile strength is applied thereto.
